**ALKYL ETHER OF LINEAR METHYLENE
NITRAMINES**

NITRAMINES

William A. Gey and Robert W. Van Dolah, China Lake,
Calif., assignors to the United States of America as
represented by the Secretary of the Navy
No Drawing. Filed Jan. 27, 1953, Ser. No. 333,623
1 Claim. (Cl. 260—584)
(Granted under Title 35, U.S. Code (1952), sec. 266)

The invention described herein may be manufactured and used by or for the Government of the United States of America for governmental purposes without the payment of any royalties thereon or therefor.

The invention relates to new chemical compounds, 15 more particularly, it relates to ethers of linear methylene nitramines of the structure

wherein R_1 is selected from the group consisting of hydrogen, alkyl or alkoxy, R_2 is alkoxy and x is an integer.

An objective in the production of high explosives is an explosive which is relatively insensitive to detonation by mechanical shock and highly sensitive to detonation by explosive shock. A number of explosives which have high explosive efficiency are unsuitable for military or commercial use because their sensitivity to mechanical shock makes handling of them extremely hazardous. An expedient which has been used to overcome this difficulty in a number of explosive compositions is the incorporation therein of an additive which reduces the sensitivity of the explosive to mechanical shock. For example, paraffin hydrocarbons have been added to such explosives as tetranitromethane; nitro aromatic hydrocarbons have been added to blasting gelatine; and celulose acetate has been added to nitroglycerin for the above purpose. A difficulty attendant to the incorporation of additives in explosive compositions is the fact that ordinarily certain desirable qualities such as brisance, density and others are sacrificed. Accordingly, this procedure ordinarily results in a compromise between various properties of the explosive.

Petroleum waxes have been used in the past as additives to such high explosives as RDX. Although these additives reduce the sensitivity of the explosive to mechanical shock, they also produce a final composition which is excessively sticky. This latter characteristic makes processing difficult. In addition, their incorporation in the explosive results in a lowering of its overall density, thus resulting in a less compact explosive with resultant loss of explosive power.

It is, therefore, an object of this invention to provide additives for explosives which reduce the sensitivity of the explosive to mechanical shock without adversely affecting other desirable explosive properties.

It is another object of this invention to provide additives for explosives which produce a product which is not tacky or sticky.

It is still another object of this invention to provide additives for explosives which produce a product of increased density.

It is a further object of this invention to provide additives for explosives which produce a final product having good storage stability.

2

The additives of this invention which meet the above objects comprise alkyl ethers prepared from NSX(1-nitroxy - 2,4,6-trinitro - 2,4,6 - triazaheptane), ATX(1,7-di - nitroxy - 2,4,6 - trinitro - 2,4,6 - triazaheptane), 1-nitroxy - 2,4,6 - trinitro - 2,4,6 - triazadecane and 1,9-dinitroxy - 2,4,6,8 - tetranitro - 2,4,6,8 - tetraazonane. The ethers found most suitable are those having from four to eight atoms in the alkyl chain. The compounds are prepared by heating an excess of the appropriate alcohol with NSX, ATX, 1-nitroxy-2,4,6-trinitro-2,4,6-triaza-decane, 1,9-dinitroxy-2,4,6,8-tetranitro-2,4,6,8-terazano-nane, or other appropriate linear methylene nitramine

The following specific examples will serve to illustrate the preparation of the compounds of the invention:

Example 1

The butyl ether from NSX was prepared by adding 5 grams of NSX to 20 cc. of n-butyl alcohol and stirring the mixture at 95° C. until solution was effected. The solution was poured into an equal volume of benzene, cooled at 0° C. for 48 hours and filtered. The product was recrystallized from methanol.

The compound has the following structural formula:

The above procedure was repeated to produce the amyl, hexyl and heptyl ethers from NSX by reacting the appropriate alcohol with NSX with the exception that the mixtures producing these three ethers were heated one hour, one and three-fourths hours and three hours respectively. The yields of butyl, amyl and heptyl ethers were 5 grams (97%), 4.4 grams (82%), 5.5 grams (97%) and 5.5 grams (94%), respectively.

Example 2

The di-n-octyl ether from ATX was prepared by heating 25 grams of n-octyl alcohol at 85° C. for 2 hours with 5 grams of ATX to give complete solution. The solution was filtered while hot, cooled, refiltered at room temperature and further purified. The compound formed has the following formula:

The above procedure was repeated to produce di-n-butyl, di-n-amyl, di-iso-amyl, di-n-hexyl and di-n-heptyl ethers from ATX by reacting the appropriate alcohol with ATX.

Example 3

The methyl ether from 1-nitroxy-2,4,6-trinitro-2,4,6-triazadecane was prepared as follows:

4.6 grams of crude 1-nitroxy-2,4,6-trinitro-2,4,6-triacyclic decane were heated on a steam bath with stirring with 2.7 ml. of methyl alcohol. About 10 minutes were needed for solution and the mixture was heated an additional 5 minutes, then cooled. A solid mass of crystals was recovered. After warming slightly the product was filtered, dried in air and recrystallized from methyl alcohol. 4 grams of the ether were recovered, amounting to a yield of 91%. The compound has the following structural formula:

Example 4

The di-n-hexyl ether from 1,9-dinitroxy-2,4,6,8-tetranitro-2,4,6,8-tetraazanonane was prepared as follows:

15 cc. of 1,9-dinitroxy-2,4,6,8-tetranitro-2,4,6,8-tetraazanonane were mixed with 4 grams of n-hexyl alcohol and the mixture stirred at 120° C. until complete solution and for 20 minutes thereafter. The mixture was cooled at 0° C. for one hour, filtered and the ether recovered by recrystallization for methanol. 3.9 grams of the ether were obtained, amounting to an 89% yield.

The compound has the following structural formula:

Example 5

Examples 1 to 4 show the general methods of preparing the compounds of the invention, the specific properties of these being given as follows:

ETHERS FROM NSX

	Percent nitrogen (calculated)	Percent nitrogen (found)	Melting point (degrees C.)
butyl.....	27.09	27.77	101-102
amyl.....			103-104
hexyl.....			95.5-96.5
heptyl.....	23.86	23.96	88.5-89.0

ETHERS FROM ATX

di-n-butyl.....	20.50	22.25	80-82
di-n-amyl.....			82-83
di-iso-amyl.....			83.5-85
di-n-hexyl.....			77-78
di-n-heptyl.....			67-69
di-n-octyl.....	16.99	17.50	80-82

4

ETHERS FROM 1-NITROXY-2,4,6-TRINITRO-2,4,6-TRIAZADECANE

methyl.....			92-93
di-n-hexyl.....			155-155.5

10 As disclosed in the co-pending application of William A. Gey, entitled "Explosive Compositions," Serial

No. 333,622, filed in the U.S. Patent Office January 27, 20 1953, which has matured into Patent No. 2,982,639, issued May 2, 1961, the addition of the above ethers to such high explosives as RDX results in an explosive of improved density and therefore higher explosive power. In addition, the presence of these ethers renders the explosive less sensitive to mechanical shock. For example, 25 such a composition is disclosed in the above application having a ballistic mortar value 138.1% that of TNT, a density of 1.661 grams per cc., a heat of explosion of 1230 calories per gram and an impact sensitivity close 30 to that of composition A. Further, the addition of the present compounds to explosives does not render them sticky or tacky so that they can be readily processed.

What is claimed is:

The ether of the formula
